UNITED STATES PATENT OFFICE.

WILLIAM RITSCHARD, OF DETROIT, MICHIGAN.

MOP.

Application filed June 26, 1922. Serial No. 571,046.

To all whom it may concern:

Be it known that I, WILLIAM RITSCHARD, a citizen of the United States, and residing at Detroit, in the county of Wayne and State 5 of Michigan, have invented a new and Improved Mop, of which the following is a specification.

This invention relates to means in the nature of a mop for cleaning plates, pans, kettles and other utensils, and a so for cleaning 10 floors, and its object is to provide a handle, a cloth or swab, and a resilient wire holder to attach the swab or cloth to the handle.

This invention consists of a handle whose 15 size shall depend upon the use to which the cleaner is to be put, whether for mopping floors or for cleaning table china or kitchen utensils, the handle having a longitudinal hole in one end, a wire bent upon itself 20 to form a loop and having its ends extending into the hole in the handle, a cloth or swab extending through the loop of the wire and secured to the handle thereby, the ends of the wire being bent back upon themselves 25 to form eyes to hold the wire in the handle.

It also consists in a handle of the character described recessed to give access to the eyes at the ends of the wire holder, and in a metal reinforcement adapted to be 30 inserted in the longitudinal hole in the handle.

It further consists in the details of construction illustrated in the accompanying drawing and particularly pointed out in the 35 claims.

In the drawing, Fig. 1 is an elevation of this improved plate cleaner, a portion of the handle being broken away to more clearly show the internal construction. Fig. 40 2 is another elevation taken from the right in Fig. 1. Fig. 3 is a central longitudinal section of a modified form of this invention. Fig. 4 is an elevation thereof taken from the left in Fig. 3. Figs. 5 and 6 are sections on the lines 5—5 and 6—6 of Fig. 1. Fig. 7 is a section on the line 7—7 of Fig. 3. Figs. 8 and 9 are elevations of two forms of cloth-holders.

Similar reference characters refer to like 50 parts throughout the several views.

The handle 1 shown in Figs. 1, 2, 5 and 6 may be of any desired length and is preferably of wood having a longitudinal slot 2 in one end and being preferably tapered as 55 indicated in Fig. 2. Mounted in this slot is an insert shown in cross section in Figs.

5 and 6, made by bending a sheet of metal to form the sides 3 and 4 and ends 5 and 6 of a flat tube, one edge 7 of the sheet being permitted to project and being sharpened 60 so that it may be used as a plate scraper. The sharp edge is preferably at an angle to the line of the handle so as to be more convenient for scraping kettles and pans. Rivets 8 may be employed to hold the insert 65 in position.

Any desired form of swab may be used in connection with this handle, a piece of cloth 10 being indicated in dotted lines in Fig. 1, although spinners' waste or unraveled rope 70 or any other fibrous material may be employed. To secure this swab in position a loop of resilient wire is employed, that shown in Fig. 1 consisting of a resilient ring 11, two arches 12 and the legs or straight 75 portions 13 whose ends are in the form of eyes 14. The fabric or other fibrous material is inserted in any desired manner within the looped outer portion of this holder and the legs 13 are pushed into the insert until so the eyes 14 pass the inner edge of the inserted tube when they spring out over this edge and thus retain the swab in position. The handle is shown provided with recesses 15 so these eyes may be pressed toward each 85 other to release this wire holder.

The sides 3 and 4 are shown to be formed with ears 16 at their outer ends and the ring 11 is adapted to force a portion of the swab into the space between these ears thus securing the parts together. A wire 17 may be bent to form an eye 18 around the point of connection of the eye 11 and the arches 12 and this wire may be pushed through the swab into the metal insert, as indicated in 95 Figs. 1 and 2, when the legs 13 are inserted, until the bent inner end 19 of this wire snaps into the slot 20 in the plate 3. The handle is formed with a recess 21 so that this end 19 may be released with the eyes 14 to permit removal of the swab and its holder. 100

As the cloths or swabs may be of different bulks, the distance the loops must extend from the handle will vary. For this reason I may provide a second slot 40 in the insert 105 and handle and notches 41 in the insert to receive the eyes 14 at the ends of the loop. I prefer to leave tongues 42 at the lower ends of these notches 41 to prevent the eyes from slipping through the notches 41. 110

It will be understood that the shape of the loop of this swab holder may be varied

in many ways. In Fig. 8 the wire is bent to form the simple bow 23 intermediate the ends of this holder and when this is employed the slot 20 and recess 21 are unnecessary. In Fig. 9 the wire is bent to provide fingers 24 which are adapted to grip the fabric firmly. The remainder of these holders will be as above described.

In Figs. 3, 4 and 7 a modified construction is shown. The handle 26 is formed with a central bore which receives a tubular insert 27 and the handle has a recess 28 at the inner end thereof. A thimble is attached to the end of the handle and consists of a cylindrical portion 29 and a flattened portion 30, the rivet 31 securing the thimble in position. The wire holder consists of a loop 33 through which the cloth 34 extends and two legs 35 which terminate in eyes 36 adapted 20 to engage under the lip 37 which may be formed on the inner end of the insert 27 and bent outward after the insert is in place to keep it there.

As stated before, the swab 34 may vary in 25 size and therefore I prefer to form the insert 27 with a notch 43 to receive the eyes 36 and form the handle with a recess 44 through which the eyes are accessible.

Many other changes may be made in the 30 construction of this device without departing from the spirit of my invention as set forth in the following claims.

I claim:—

1. A mop comprising a handle formed 35 with a longitudinal slot in one end, a metal insert mounted in the slot and formed of a strip of sheet metal bent upon itself to form spaced sides, the edge of one side extending from the slot in the handle to constitute a 40 scraper, a wire holder bent intermediate its length to form a loop and having its ends extending into said insert, and a swab held onto the end of the handle by said loop.

2. A mop comprising a handle formed 45 with a longitudinal slot in one end, a metal

insert mounted in the slot and formed of a strip of sheet metal bent upon itself to form spaced sides, the edge of one side extending from the slot in the handle to constitute a scraper, a wire holder bent intermediate its 50 length to form a loop and having its ends extending into said insert, and a swab held onto the end of the handle by said loop, the ends of said wire holder being bent to engage the inner edge of the insert, and the 55 handle being formed with recesses to give access to said ends of the holder.

3. In a mop, a handle, a hollow metal securing device secured to the end of the handle, a wire holder bent to form a loop and 60 extending through the securing device and having its ends bent to secure the holder in the handle, and a swab secured to the end of the handle by the loop, the handle being recessed at the opposite end of the securing 65 device from the swab to give access to the ends of the holder to release it and the swab.

4. A mop comprising a handle formed with a longitudinal recess in one end, a metal insert mounted in the recess and formed of 70 a strip of sheet metal bent along lines parallel to the handle, the sides of the insert being spaced apart, a looped wire holder having its sides extending into the slot and having its ends bent to secure the loop to 75 the handle, a swab within the loop which is distorted to give additional holding power, and a wire pivoted to the loop and extending into the insert.

5. A mop consisting of a handle having a 80 longitudinal recess in one end, a resilient wire loop slidably mounted in said recess of the handle, and a swab secured to the end of the handle by the loop, said loop having bent ends to engage shoulders at the end of 85 the recess in the handle to hold the loop, said handle being further recessed to give access to said ends to release the same from said shoulders.

WILLIAM RITSCHARD.
